UNITED STATES PATENT OFFICE.

ULRICH BISCHOF, OF HORGEN, SWITZERLAND, ASSIGNOR, BY MESNE ASSIGNMENTS, TO SMYTH MANUFACTURING COMPANY, OF HARTFORD, CONNECTICUT, A CORPORATION OF CONNECTICUT.

SADDLE FOR THE TABLES OF THREAD-STITCHING MACHINES.

Application filed March 7, 1925, Serial No. 13,809, and in Switzerland November 20, 1924.

The saddles for the tables of thread-stitching machines for supporting the sheets have an obtuse angle of about 70° . This has the great disadvantage that the sheets before being laid on the saddle always have to be forcibly pulled apart by hand, in order that they shall rest properly on the saddle and will not be turned over at the fold, when the sheets are brought under the stitching rail and the needles for being stitched. This opening and laying on of the sheets requires a considerable amount of practice on the part of the worker, if the full number of revolutions of the machine are to be utilized. A further disadvantage of the blunt saddle is, that the preliminary puncturing needles and the sewing and hooked needles must pass through the sheets at an inclination of about 35° , whereby the sheets are easily forced backwards in the machine by the preliminary puncturing needles and consequently the holes will not be in the middle of the fold and the sewing and hooked needles tend to be bent, owing to this inclined position when passing through the sheets, and thus easily break.

Another saddle for the table of a thread-stitching machine has the form of an arm and consists of two parallel plates screwed together, the preliminary puncturing needles being guided between the said plates and having at the top semicircular grooves for the reception of the sewing needles. This saddle has the disadvantage that the thread laying means used successfully in all other stitching machines for taking up the thread from the sewing needle and transferring it to the hooked needle cannot be fixed and that therefore semicircular sewing needles must be used. These needles have however the great disadvantage that they break very easily, all the more since the needles for making the preliminary punctures are made very thin and are only operated from one side, so that more particularly the thicker sheets are insufficiently punctured beforehand, which causes still more needle breakages.

The subject of the present invention is a sharp ridged table saddle with a plate, the place of entry of which for the needles forms an angle of approximately 35° and is provided with an inclined surface, on which the stitching thread slides upwards. When such a sharp ridged table saddle is used, the sheets need not be opened out before being laid on,

which considerably increases the output of the worker. Owing to the sharp ridged saddle the preliminary puncturing needles and the sewing and hooked needles can be arranged so as to be at least approximately vertical, which on the one hand completely prevents the sheets being displaced when they are being punctured and on the other hand makes it possible to use straight sewing and hooked needles. It is also impossible for the sheets to be displaced laterally, when the needles enter the holes, and for the needles to be broken. A further advantage of the sharp ridged table saddle consists in this that the pivotal axis of the table saddle is placed above the saddle so that the saddle, when swinging outwards, also swings upwards and during the subsequent inward swing strips the stitched sheets downwards and thus at the same time acts as a stripper. This obviates the necessity of providing a separate stripper and the machine is made less complicated and cheaper.

The subject of the invention is shown in the accompanying drawings, in which

Figs. 1 and 2 are a front and side view of the same as applied to a thread-stitching machine,

Figs. 3 and 4 show the saddle acting as a stripper,

Figs. 5 and 6 show the saddle in front and side elevation,

Fig. 7 is a front elevation of the saddle plate.

Fig. 8 is an enlarged side elevation of the saddle.

Fig. 9 is an enlarged side elevation of the saddle plate.

Fig. 10 is a side view of the saddle showing it in a position intermediate that shown in Figs. 3 and 4.

The saddle of the table for the sheets is shown in the drawing as forming part of a thread-stitching machine, which works with a pair of needles having a vertically upward and downward motion and consisting of a sewing needle 11 and a hooked needle 12. By this pair of needles the sheets are only stitched in one place; two or more pairs of needles may, however, be provided according to the length of the sheets to be stitched. The machine has two lateral frames 1 and 2, in which the horizontal shaft 3 is journalled. On the shaft 3 are fixed the cam discs 4 and 5. In the

frames a bar 10 is guided so as to be capable of sliding upwards and downwards, which bar carries the needles 11 and 12 and the rollers 13 and 14, which engage with the cams 7 to the right and left. In guides at the top of the lateral frames blocks 16 and 17 are slideable, in which a shaft 15 is journaled, rollers 18 and 19 on the shaft 15 resting at either side on circumferential cams 20 and 21 on the cam discs 4 and 5. On the shaft 15 are mounted the arms 22 and 23 supporting at the bottom the transverse member 26 of the table, each of the arms being provided with a roller 24 and 25 respectively. The roller 24 engages with the cam 6 of the left-hand disc 4 and the roller 25 with the cam 6 of the right-hand disc 5. In the transverse member 26 of the table a rail 27 is guided so as to be capable of an upward and downward motion. The rail 27 has rollers 28 and 29, one at either end, which rollers engage with the cams 8 of the discs 4 and 5, and preliminary puncturing needles 30. In the transverse member 26 is also journaled a bar 31 provided with a roller 33 and supporting the thread laying member 32, which bar is drawn by a tension spring 34 against the cam disc 5 and is moved to and fro in the lateral direction by a cam 35 screwed to the said disc.

30 The transverse member 26 of the table has a plate 36 the top of which is formed in its longitudinal direction as a closed angle constituting a sharp edge regularly pointed from both sides and serving as supporting saddle 35 for the fold of the sheets (see Figs. 6-9), the top of the said plate having also a slipping surface *c* on which the thread loops are lead off outwardly, pinching in of the said loops being thereby prevented. A cover plate 37 is provided for protection of the sheets. A rail 38 is guided in the lateral frames 1 and 2 so as to be capable of an upward and downward motion and has rollers 39 and 40 at the left-hand and right-hand ends, which engage with the corresponding cams 9 of the discs 4 and 5, and supports the thread gripping pin 41 and a bar 42. The bar 42 has guide rollers 43 and 44 at the left-hand and right-hand ends, which bear against the cams 45 and 46 screwed on the cam discs 5 and 4, the cam 45 displacing it to the left and the cam 46 to the right, whereby the thread gripping pin is caused to be opened and closed by an inclined surface 47 on the bar 42.

55 The saddle described above operates as follows:

The sheet 48 which is to be stitched (Figs. 1 and 2) is laid on the saddle 36 which is swung out to the left (Fig. 3) and, on the cam discs 4 and 5 being turned in the direction indicated by the arrow *P* (Fig. 2), the saddle together with the sheet is brought by the cams 6 under the stitching rail 49. The saddle is thereupon raised by the two cams 20 and 21 on the cam discs 4 and 5 towards the stitching

rail 49, whereby the fold of the sheet is forced exactly into the middle of the saddle (Figs. 1 to 4). In this position the preliminary puncturing needles 30 puncture the sheet vertically from below, through the bar 27 with the rollers 28 and 29 being moved upwards by the cams 8. Thereupon the sewing and hooked needles 11 and 12 enter also vertically, but from above the holes punctured by the preliminary puncturing needles, the bar 10 with the rollers 13 and 14 being moved downwards by the cams 7 to the left and right. The thread laying member 32 thereupon moves to the left through the bar 31 with the roller 33 being forced by the cam 35 to the left, the thread which has been introduced into the sheet by the sewing needle 11 in a known manner being seized by the thread laying member 32, carried across to the hooked needle, caught by the latter, also in a known manner, and drawn up through the sheet. During this operation the thread is taken in and drawn tight by the thread tightening bar 38 in a known manner and at the correct moment is liberated by the thread gripping pin 41 and gripped again. The saddle thereupon moves downward again vertically and immediately performs the outward swinging movement again for receiving a fresh sheet whereby the saddle, when swinging outwards changes its position in vertical direction upwards while the front half of the previously stitched sheet still lays on the saddle, the saddle releasing afterwards the said half when it is in the outmost position. This half is inclined in a certain degree (see Fig. 3) and will be pressed against the stock of stitched sheets by the saddle carrying a fresh sheet when it again moves inwardly. The said sheet together with the staple is pressed rearwardly for the thickness of a sheet, the sheet half projecting from the previously stitched sheet being firstly touched by the back wall of the rail 27 carrying the puncturing needles (see Fig. 10) and then also immediately by the back wall of the saddle plate 36 and being thereupon pressed rearwardly.

It will be seen from the foregoing that in a saddle as described displacing of the sheet out of its folding center and also the pinching in of thread in the saddle are excluded, and that the sheets, before laying them upon the saddle, need no longer be opened out by hand and in spite of this rests correctly on the saddle. This is a remarkable advantage, since the worker can feed on fresh sheets at a considerably greater rate and will therefore turn out more work. By the puncturing needles working vertically any displacement of the sheets during the puncturing operation is prevented and also any bending of the sewing and hooked needles, so that breakages due to this cause are practically excluded. The swinging motion of the saddle from a pivotal axis lying above it is also of great advantage,

as this enables the saddle to act at the same time as a pressing-on member for the sheets and it is therefore not necessary to provide special means for this purpose. A further advantage of the improved saddle consists therein, that the shaft located over the saddle not only is turnable but also vertically movable, so that the saddle brings the sheets not only under the needles, but simultaneously 10 presses the same before the stitching operation into the fold.

What I claim is:

1. A table-saddle for thread-bookstitching machines, including a single plate having a 15 wedge shaped upper supporting edge of about 35° and provided with grooves for housing puncturing needles and with a sloping surface below the supporting edge on the side having the said grooves to lead away the 20 thread loops outwardly to prevent pinching in of the thread loops, the said table-saddle being carried by swinging arms fixed to a horizontal shaft located over the saddle.

2. A table-saddle for thread-bookstitching 25 machines, including a single plate having a wedge shaped upper supporting edge of about 35° and provided with grooves for housing puncturing needles and with a sloping surface below the supporting edge on the 30 side having the said grooves to lead away the thread loops outwardly to prevent pinching in of the thread loops, the said table-saddle being carried by swinging arms fixed to a horizontal shaft located over the saddle and 35 vertically movable to obtain a vertical movement of the saddle for pressing the sheets in the folding center.

3. A table saddle for thread book stitching 40 machines, including a single plate having a wedge shaped top edge of about 35° substantially uniformly pointed from both sides towards the top edge, both wedge faces being of sufficient width to spread open the sheet immediately beneath the fold, a hooked needle 45 vertically movable and capable of piercing of the fold of the sheet without damaging the inner face of the sheet, the lower parts of which hang down in an angle less than 35° , a horizontally movable thread layer for the 50 thread loop, and a sloping undercut surface on the working side of the thread layer below the supporting edge and extending from the working plane of the needle to the front wedge surface of the top edge to lead away 55 the thread loop outside of the working plane of the needle forwards and upwards upon the

said wedge surface to prevent pinching in of the thread loops.

4. A table saddle for thread book stitching machines, including a single plate having a 60 wedge shaped top edge of about 35° substantially uniformly pointed from both sides towards the top edge, both wedge faces being of sufficient width to spread open the sheet immediately beneath the fold, a hooked 65 needle vertically movable and capable of piercing of the fold of the sheet without damaging the inner face of the sheet, the lower parts of which hang down in an angle less than 35° , a horizontally movable thread layer 70 for the thread loop, a sloping undercut surface on the working side of the thread layer below the supporting edge and extending from the working plane of the needle to the front wedge surface of the top edge to lead 75 away the thread loop outside of the working plane of the needle forwards and upwards upon the said wedge surface to prevent pinching in of the thread loops, a shaft located 80 over the saddle and vertically movable and swinging arms carrying the saddle and fixed to the said shaft.

5. A table saddle for thread book stitching machines, including a single plate having a 85 wedge shaped top edge of about 35° substantially uniformly pointed from both sides towards the top edge, both wedge faces being of sufficient width to spread open the sheet immediately beneath the fold, a hooked needle 90 vertically movable and capable of piercing of the fold of the sheet without damaging the inner face of the sheet, the lower parts of which hang down in an angle less than 35° , a horizontally movable thread layer 95 for the thread loop, a sloping undercut surface on the working side of the thread layer below the supporting edge and extending from the working plane of the needle to the front wedge surface of the top edge to lead 100 away the thread loop outside of the working plane of the needle forwards and upwards upon the said wedge surface to prevent pinching in of the thread loops, a shaft located over the saddle and vertically movable, swinging arms carrying the saddle and fixed to the said 105 shaft and cams provided on both sides of the machine frame to vertically move the said shaft without levers and connecting rods.

In testimony whereof I have affixed my signature.

ULRICH BISCHOF.
